(57) **CLAIM**

The ornamental design for a display screen with icon, as shown and described.

DESCRIPTION

The file of this patent contains at least one drawing executed in color. Copies of this patent with color drawing will be provided by the Office upon request and payment of the necessary fee.

FIG. 1 is a front view of a display screen with icon showing our new design;

FIG. 2 is a second embodiment thereof; and,

FIG. 3 is a third embodiment thereof.

The broken lines of uneven length show the display screen and form no part of the claimed design.

1 Claim, 3 Drawing Sheets
